UNITED STATES PATENT OFFICE

ISIDOR FRED PETIGOR, OF NEW YORK, N. Y.

ADVERTISING DEVICE

Application filed June 3, 1929. Serial No. 368,115.

This invention relates to flexible advertising devices of a pictorial character. It is one of the objects of the invention to produce a device which shall be capable of being set up in rigid and stiff position for display purposes and which can also be readily dismantled and rolled up for transportation and shipment. The foregoing and other objects of the invention will appear to those skilled in the art to which it appertains by a consideration of the following description of one embodiment thereof taken in connection with the accompanying drawings in which

Figure 1 is a rear perspective view of a pictorial advertising device showing one embodiment of the invention;

Figure 2 is a vertical sectional view taken on the broken line 2-2 of Figure 1;

Figure 3 shows the device in dismantled position preparatory to rolling it up for shipment;

Figure 4 shows the device with the rolling for shipment nearly completed;

Figure 5 is an enlarged detailed view partly broken away, of the means used for holding the front and rear sheets together; and

Figure 6 is an enlarged detailed view, partly broken away, of the means used for holding the front and rear sheets together and for holding the lateral stiffening means to the sheets.

Referring to the drawings more in detail, 11 represents a member of sheet material and preferably a light weight paper of sufficiently high quality to receive a printed impression and which can be rolled without cracking or other injury. The sheet member 11 is shown as of irregular contour or outline as it is for use with such irregular forms that the invention is of most value. A second member 12 of sheet material of the same general contour as the member 11 has one end secured to one end of the member 11 as at 13 by pasting or gluing or in any other suitable manner. The sheet material member 12 is used for reinforcing and strengthening the device as a whole and is preferably of heavy weight paper such as kraft paper. A stiffening member 14 is secured to the sheet members 11 and 12 where they are fastened to each

other and is provided with a longitudinal slot 15 so that the member 14 is divided into two strips 16 and 17 for the greater portion of its length. The lower strip 16 is secured to the members 11 and 12 but the upper strip 17 is not fastened thereto and is resiliently movable to a limited extent in an up and down direction. The member 14 is preferably formed from wood as such material is inexpensive, lends itself readily to the fabricating operations and has the necessary resiliency. Other materials, however, may be used instead of wood if so desired. Another stiffening member 18 is secured to the other end of the sheet member 11 preferably only at the upper portion of the member 18 so that the sheet member 12 which is slightly shorter than the member 11 may slip between the stiffening member 18 and the sheet member 11.

The sheet members 11 and 12 are also provided with a plurality of means for holding them in superimposed relation while permitting a certain amount of sliding movement therebetween. Some of these means also cooperate with intermediate lateral extending stiffening members and others are used separately from such stiffening members. Those used for holding only are designated by the reference character 19. The part 19 may be made of sheet metal bent into the form of a T, passed through a fastening tape or strip of paper 20, which tape is glued to the member 11 the plies of the part 19 passing through an opening 21 in the sheet member 12 and being bent outwardly to prevent withdrawal as shown in Figure 5. It will be noted that the opening 21 is of somewhat greater length than the part 19 extending therethrough so that the part 19 and the sheet member 11 secured thereto are free to move up and down with respect to the member 12 to a limited extent. Another type of holding means 22 is shown in detail in Figure 6. The part 22 is of sheet metal bent into a closed loop and fastened to the sheet member 11 by means of a tape 23. The loop 22 extends through an opening 24 in the sheet member 12 which is of somewhat greater length than the loop 22. That part of the

opening of the loop 22 which extends out from the sheet member 12 is adapted to receive and retain or hold one end of a laterally extending stiffening member or bar 25 preferably of wood. It will be seen that the part 22 by means of the member 25 prevents separation of the two sheet members 11 and 12 and also co-operates with the members 25 to provide a stiffening effect for the device as a whole. As will be noted from Fig. 1, the retaining devices 19, as well as the devices 25, are arranged in pairs near opposite edges of the sheets 11 and 12, and there are a plurality of such pairs.

In order to stretch the sheet member 11 for display purposes a vertically disposed strut is provided which may consist of an upper element 26 and a lower element 27. The upper end of the element 26 and the lower end of the element 27 are slotted as indicated at 28 to engage the shanks of tacks 29 such as thumb tacks or upholstery tacks driven into the stiffening members 14 and 18. The ends of the elements 27 and 28 are also rabbeted as at 30. One of the elements as 26 is slotted longitudinally as indicated at 32 and the other element 27 is provided with a bolt 33 which extends through the slot 32 and has a wing nut 34 whereby the two elements 26 and 27 may be clamped together. The two elements 26 and 27 of the vertical strut are preferably formed from wood as such material is inexpensive, readily fabricated, and the portions adjacent the slot 32 are resilient for engaging the piece inserted therebetween as will be explained hereinafter. An easel-like support may be provided by two pieces of wood 35 and 36. One end of the piece 35 is pivoted to the element 27 as at 37 and the other end of the piece 35 is pivoted as at 38 to one end of the piece 36. The other end of the piece 36 is adapted to be inserted in the slot 32 and to be frictionally held therein the end being preferably beveled as at 39 to facilitate its ready insertion into the slot.

In operation the two sheet members 11 and 12 are unrolled. The two elements 26 and 27 of the vertical strut are then slipped along with their ends under the tacks 29 and pushed apart to stretch the member 11 out flat. When the stretching tension, which is prompted by the resiliency of the slotted bar 14, is sufficient the wing nut 34 is tightened to hold the parts in this stretched position. The pieces 35 and 36 are then set at the proper angle to constitute a sort of easel and the beveled end 39 is inserted in the slot 32 where it is frictionally held.

To dismantle and pack the device the beveled end 39 is removed from the slot 32 and the wing nut 34 is loosened so that the strut can be removed by sliding the upper and lower elements together. These parts are then folded and placed transversely of the device adjacent to the stiffening member 14 as shown.

in Figure 3. The device is then rolled up, the appearance when the rolling is nearly completed being as in Figure 4. It will be seen in Figure 3 that the parts 19 extend thru the openings 21 near the upper portions thereof but as the sheet members 11 and 12 are rolled together, the member 11 being on the outside will gradually slip back until the parts 19 extend through the lower portion of the openings 21 as seen in Figure 4. This arrangement makes it possible to hold the two sheet members 11 and 12 in superimposed relation while permitting the slight movement or sliding with respect to each other which is necessary in rolling the two sheets without cracking, bending or injury. The rolled up device may then be inserted in a mailing tube or transported in any other suitable manner.

From the foregoing it will be seen that a device has been provided which can be promptly set up for display and also promptly dismantled for transportation and shipment. Furthermore it is given a rigidity and stiffness in both directions, longitudinally and laterally. The member 11 which carries the pictorial representation may be of light weight, suitable for printing and easily bent without danger of cracking or injuring the illustration thereon. The member 12 may be stiff, strong, and of considerably greater thickness than would be suitable for printing and bending. While these are the chief advantages there are others which need not be specifically enumerated as they will be obvious to those familiar with such devices.

It will further be observed that the novel advertising device comprises two plies or sheets of irregular shape so connected as to afford relative movements between the plies during the operations of unrolling and rolling up the device; that one of the plies or members of sheet material comprises a face for advertising matter, the other ply serving as a backing for the ply bearing the advertisement; and that the means for stretching, stiffening and supporting the sheet material or plies is collapsible and includes an element on which the two flexible plies or sheets may be conveniently rolled up.

Various constructional changes may be made without departing from the spirit and scope of the invention as herein set forth and particularly pointed out in the appended claims.

I claim:

1. A pictorial advertising device comprising a member of sheet material, a stiffening member extending across one end of said sheet material member, a second stiffening member extending across the other end of said sheet member and having a longitudinal slot therein to provide two parallel strips, one of said strips being secured to the sheet material member, and an adjustable strut extending between the other strip and the first named

stiffening member for holding them apart.

2. A pictorial advertising device comprising a pair of members of irregular contours formed from sheet material, means securing said members together at one end thereof, means for holding the rest of the members in superimposed relation while permitting a limited amount of sliding movement therebetween, a plurality of lateral stiffening members extending across the surface of one of said sheet material members, and a strut device assisting to stretch said sheet material members from end to end and hold them in stretched position.

15 3. A pictorial advertising device comprising a pair of members of irregular contours formed from sheet material, said members being fastened together at one end thereof, means for holding the rest of the members in superimposed relation while permitting a limited amount of sliding movement therebetween, a plurality of lateral stiffening members extending across the surface of one of said sheet material members, there being a 20 stiffening member secured to each end of one of said sheet material members, one of said end members having a certain amount of resiliency, and stretching means extending between said end stiffening members for holding them resiliently apart.

25 4. A pictorial advertising device comprising a member of light weight printing paper stock of irregular contour with a pictorial representation thereon, a member of heavy weight kraft paper stock of similar contour, said members being fastened together at one end thereof, means for holding the rest of said members in superimposed relation while permitting a limited amount of sliding movement therebetween, lateral stiffening members extending across each end of said light weight member, an adjustable strut extending between said stiffening members, one of said stiffening members being resilient to the 30 action of the strut during lengthwise adjustments, and a plurality of intermediate stiffening members extending laterally across the heavy weight member.

40 5. A pictorial advertising device comprising two plies or sheets of irregular shape connected to afford relative movements between the plies during the unrolling and rolling up of the device, one ply providing a face for advertising matter and the other 45 ply serving as a backing, and means for preventing separation of the plies when the device is open, in combination with supporting means.

60 6. A pictorial advertising device comprising two plies or sheets of irregular shape connected to afford relative movements between the plies during the unrolling and rolling up of the device, one ply providing a face for advertising matter and the other 65 ply serving as a backing, and means for preventing separation of the plies when the device is open, in combination with supporting means.

70 ration of the plies when the device is open, in combination with collapsible means for maintaining the plies in flat condition when the device is open.

75 7. A pictorial advertising device comprising two plies or sheets of irregular shape connected to afford relative movements between the plies during the unrolling and rolling up of the device, one ply providing a face for advertising matter and the other 80 ply serving as a backing, and means for preventing separation of the plies when the device is open, in combination with collapsible means for maintaining the plies in flat condition when the device is open, said means comprising an element on which the plies may be conveniently rolled up.

85 8. A pictorial advertising device, comprising two plies of sheet material, one arranged to back the other, a stiffening member extending across one end of the sheets, a second stiffening member extending across the opposite ends of the sheets, said second member being resilient, stretching means extending between said stiffening members for holding them apart and maintaining the sheets in stretched condition, a plurality of supporting members spaced apart between the two end stiffening members and in substantial parallelism therewith, and devices cooperating with the side edge portions of the sheets to prevent them from separating while affording relative sliding movements between the sheets during rolling and unrolling operations.

90 9. A pictorial advertising device, comprising two plies of sheet material, one arranged to back the other, a stiffening member extending across one end of the sheets, a second stiffening member extending across the opposite ends of the sheets, said second member being resilient, stretching means extending between said stiffening members for holding them apart and maintaining the sheets in stretched condition, a plurality of supporting members spaced apart between the two end stiffening members and in substantial parallelism therewith, and devices cooperating with the side edge portions of the sheets to prevent them from separating while affording relative sliding movements between the sheets during rolling and unrolling operations, said devices being permanently connected with the sheets and certain of said devices providing an attaching means for said supporting members.
